PAGE 3

FIG. 4

FIG. 1 is a perspective view of a microfilmer showing my new design;

FIG. 2 is a perspective view showing the rear thereof;

FIG. 3 is a front elevation view thereof;

FIG. 4 is a perspective view thereof similar to FIG. 2 but showing the shelf and hopper thereof in operating position, a fragment of the hopper being omitted for purposes of illustration; and

FIG. 5 is a fragmentary cross-sectional view taken along line 5—5 in FIG. 2.

I claim:

The ornamental design for a microfilmer, as shown.
